J. H. BECKER.
WARP TWISTING-IN MACHINE,
APPLICATION FILED NOV. 24, 1920.

1,424,276.

Patented Aug. 1, 1922.

WITNESS:

Wm. L. Russell.

INVENTOR:
John H. Becker,

John H. Becker,
ATTORNEY.

UNITED STATES PATENT OFFICE.

JOHN H. BECKER, OF BROOKLYN, NEW YORK, ASSIGNOR TO WARP TWISTING-IN MACHINE COMPANY, OF BROOKLYN, NEW YORK, A CORPORATION OF NEW YORK.

WARP TWISTING-IN MACHINE.

1,424,276.

Specification of Letters Patent. Patented Aug. 1, 1922.

Application filed November 24, 1920. Serial No. 426,124.

To all whom it may concern:

Be it known that I, JOHN H. BECKER, a citizen of the United States, residing at Brooklyn, in the county of Kings and State 5 of New York, have invented certain new and useful Improvements in Warp Twisting-In Machines, of which the following is a specification.

My invention relates to twisting means 10 and especially to twisting means for use in warp twisting-in machines of the class (see, for example, U. S. Patents Nos. 648,738; 675,350; 686,724; 695,566; 810,711; 911,885 and 911,886) in which the threads to be 15 joined are held with their end portions projecting in the same direction and each in angular relation to its body portion and in which the twisting means consists of two coacting members affording pad or equivalent twisting elements and one of which is movable in contact with the other so as first to twist the two end portions together and then twist said end portions about one 20 of the body portions.

My invention consists in a novel construction 25 of the twisting members whereby better twisting is accomplished as will be herein-after pointed out.

In the accompanying drawing,

Figure 1 is a sectional view taken on the 30 line 1—1 of Figure 2;

Figure 2 is a plan view of twisting and associated mechanisms substantially like those found in the Patent No. 810,711, for 35 example, above referred to;

Figure 3 is an inside or rear face view of the fixed twisting member, with its pad removed; and

Figure 4 is a fragmentary plan of said 40 member, partly in section.

A A are the body portions of two threads, one from the old warp and one from the new warp to be joined, and B B are the extremities of the threads, the threads being held in substantially the relation shown by the thread-holding portions a a of a suitable fork (see fork 59 in Patent No. 810,711, for example) and by a clamp b gripping the upturned extremities B B and by the beams 45 c, shown diagrammatically. d denotes a fork which keeps the extremities B B in proper position until the twisting of said extremities is well under way, and e designates a suitably operated knife for there-

upon severing the extremities (see also Patent No. 810,711).

The pads or twisting elements proper, one rotary and the other fixed, are designated f and g. They are formed substantially the same as in the aforementioned (Landfear) 60 Patent No. 911,886, as herein illustrated by way of example: that is, one (the movable one, g) is tapered toward its forward end and has a plain acting face, while the other (or fixed one, f) has in the lower portion of 65 its acting face a substantially triangular recess f' terminating at its lower right-hand corner in a notch f'', the acting face of the pad being continued intact both sides of the recess, as at f³, f⁴. My invention is not 70 limited to the particular form of the pads or equivalent elements, although it has been especially designed for use with pads such as I have outlined above and which, as will be seen on reference to the said Landfear 75 patent, cause the twisting to proceed from the severed extremities of the upturned end portions B B, in twisting said end portions together, and then from the point of junction between the twisted end portions and 80 the body portions of the threads, in twisting said end portions and the body portion of one thread together.

One purpose my invention particularly aims to accomplish is to prevent abortive 85 efforts on the part of the twisting means to effect the twisting: certain fibres are prone to slip rather than to roll between the twisting means as they have heretofore been constructed, and on account of this the production of a twist and the consequent uniting 90 of the threads would occasionally not occur. Another purpose is to insure the twisting together of the extremities clear to their free ends and in the finished twist prevent 95 the formation of a projecting end or "tail."

The pads f g are as usual composed of some yielding material, such as rubber, and have attaching buttons h.

The pad f is attached to a carrier device i 100 (by having its buttons interlocked with suitable notches i', therein) which is fixed to some stationary part, as a shaft j; the carrier i may have secured to it the fork d. The pad g is attached to a carrier device k 105 (by also having its buttons interlocked with suitable notches k' therein) which is fixed to a shaft l arranged to rotate par-

allel with shaft *j*. The pads are curved around the axis of a shaft *l* and the thread holding portions *aa* project within the inner perimeter of the pad *f*, being accommodated by a hole *m* in carrier *i*.

Pad *g* is in the present instance held substantially immovably on and against the flat outer face of the carrier *k*. But pad *f* is capable of a certain slight movement toward its carrier *i*, represented by a crevice *n* appearing in Figure 2. In order to accomplish the purposes indicated I have arranged the pad to have a rocking bearing on a fulcrum which opposes at the bearing of the pad thereon greater resistance to displacement of the pad from the complementary twisting member than is opposed elsewhere in the area of the pad; the exact position of this means in the present adaptation of my invention will be pointed out hereinafter. Said means consists in the example herein shown, which represents its preferred form, of a ball *o* protruding from that face of the carrier device *i* which is opposed by pad *f* and being backed by a spring *p* housed in the carrier device; the ball and spring may be contained in a ferrule *q* which has its outer edge peened inward to limit the outward movement of the ball. With reference to the pad when properly positioned, the ball is in a radius that is located between the position of the upstanding extremities *B B* before severing and the thread *A* around which the severed and twisted extremities are to be twisted, and it lies in said radius nearer the outer perimeter of pad *f* than the inner one. The pad *f* is therefore capable of rocking on a fulcrum, see-saw fashion, the fulcrum being moreover a yielding one.

When in twisting two threads together pad *g* moves around against pad *f* to effect the rolling and consequent twisting together of the extremities *B B* between it and pad *f*, the pressure of said extremities gradually increases as they are rolled around toward (and until they reach) the radial line of ball *o*. This gradual increase of pressure, due to pad *f* being held against displacement from pad *g* more in the radial line of ball *o*

than elsewhere in the area of the pad *f*, is very helpful in preventing slipping of the threads and their consequent partial or total failure to intertwist; and the pressure being greatest, as between the outer and inner perimeters of the pads, at their outer perimeters, the twisting together of the extremities clear to their very tips is uniformly insured, and this prevents the formation on the finished twist formed in the threads of a so-called "tail" or loose projecting end. After the intertwined ends pass the ball *o* the pressure on the threads decreases, and this is quite desirable, for thereupon the intertwined extremities *B B* are to be twisted with the body portion of the right-hand thread and the consequent increased bulk of the material, in order to make a good twist, requires increased spacing of the pads.

I do not wish to be limited to the exact construction herein shown and described what I claim being:

1. A thread twisting means including twisting members one of which is movable against and in wiping contact with the other, one of said members including a supporting device and a rocking pad carried by said device and affording the working face of said member and having a bearing, said device having a fulcrum for said bearing opposing greater resistance at said bearing to displacement of the pad from the other member than is opposed to such displacement elsewhere in the area of the pad.

2. A thread twisting means including twisting members one of which is movable against and in wiping contact with the other, one of said members including a supporting device and a rocking pad carried by said device and affording the working face of said member and having a bearing, said device having a yielding fulcrum for said bearing opposing greater resistance at said bearing to displacement of the pad from the other member than is opposed to such displacement elsewhere in the area of the pad.

In testimony whereof I affix my signature.

JOHN H. BECKER.
